Attorney.

UNITED STATES PATENT OFFICE

EDWARD A. CARTER, OF BUFFALO, NEW YORK

ANTI-RATTLER FOR WINDOWS

Application filed January 13, 1930. Serial No. 420,369.

This invention relates to an appliance for preventing rattling of windows.

Its object is the provision of a simple and inexpensive device of this character which can be readily applied to existing windows without materially altering their construction, without removing the sash, without disturbing the appearance of the window frame, and which permits the sash to be raised and lowered with comparative ease.

In the accompanying drawing:—

Figure 1 is a fragmentary perspective view of a window equipped with one form of anti-rattler embodying my invention. Figure 2 is an enlarged cross-section thereof taken substantially in the plane of line 2—2, Figure 1. Figure 3 is a detached perspective view of the anti-rattler device. Figure 4 is a sectional side view of a modified form of anti-rattler.

Similar characters of reference indicate corresponding parts throughout the several views.

The window frame 10, upper sash 11, lower sash 12 and window stop 13 may be of ordinary construction, the improved anti-rattler being applicable thereto without altering their construction and without removing the sash.

In the embodiment of the invention shown in Figures 1, 2 and 3, the anti-rattler comprises an upright abutment-strip 14, preferably of wood, secured to the inner lateral face 15 of the window frame in the plane of the window stop, and a spring-pressed bar or follower 16 guided on said strip for movement transversely of the frame and bearing against the adjacent stile of the lower sash to hold it firmly against the check stop and prevent rattling. In the preferred construction shown, the front edge of the abutment-strip 14 is mortised nearly from end to end of the strip to form forward extensions 17 which are provided in their opposing horizontal edges with guide grooves 18 which receive tenons 19 at the ends of the pressure-bar 16. Springs 20 are interposed between the back of the pressure-bar and the abutment-strip, those shown in the drawing being spiral springs seated at their ends in sockets formed in these members.

One of such devices may be applied to each side of the window frame, the spring-pressed bar 16 constantly urging the sash outwardly against the check stop and holding the sash firmly against rattling, the upper sash being also prevented from rattling by its connection to the lower sash through the customary sash lock not shown.

Preferably, the abutment-strip 14 is of the same width and thickness as the window stop, and in practice enough of the stop may be cut away to receive the abutment-strip, which thus forms a continuation of the stop, as shown in the drawing. This produces a neat construction which does not detract from the sightliness of the window. Depending on the size of the window, however, the abutment strip may be made in two sections and be disposed near the top and bottom of the sash, or it may extend practically the full length of the sash.

While preventing rattling the device permits the sash to be raised and lowered with little effort.

The device is exceedingly simple in construction and can be produced at small cost. As the pressure member and its springs are carried by the window frame, the device can be readily applied thereto without removing the sash and without mortising or other change of the sash.

This anti-rattler is especially desirable for the windows of office buildings, but may obviously be applied to those of various other buildings and dwellings.

In the modified form of the invention shown in Figure 4, the abutment strip 21 has transversely arranged dowel pins 22 on which the spring-pressed bar or follower 23 is guided. Springs 24 are seated in alining sockets 25 in the opposing edges of the abutment strip and the follower bar for constantly urging the latter against the sash to hold it against rattling.

I claim as my invention:—

1. The combination with a window frame and a sash including the window stop and check stop thereof, of an upright abutment-strip secured to the inner side of the window frame in the plane of the window stop and

provided in its front edge with a mortise extending nearly throughout its length, forming forward extensions at the ends of said strip, said extensions having horizontal 5 guide-grooves in their opposing edges, and a spring pressed follower-strip movable transversely of the window frame and bearing against the face of the sash and having end-tenons guided in said grooves.

- 10 2. The combination with a window frame and a sash, of a window stop applied to the frame and having a portion cut therefrom to provide a vertical space opposite the front side of the sash and in the plane of the stop, 15 an upright abutment strip detachably secured to the inner side of the window frame in said stop space and forming a continuation of the stop and flush therewith, said strip having transverse guide members thereon adjacent 20 its upper and lower ends and facing the front side of the sash, and a follower bar yielding-ly mounted on said abutment strip and having complementary guide members thereon engageable with those of the abutment strip, 25 said follower bar being flush with the window stop and movable transversely of the window frame for edgewise bearing engagement with the front side of the sash.

EDWARD A. CARTER.
